UNITED STATES PATENT OFFICE.

WILLIAM FRANKLIN STAFFORD, OF HORNSVILLE, MISSOURI.

COMPOSITION FOR REMOVING SCALES FROM STEAM BOILERS.

No Drawing.

Application filed July 20, 1926. Serial No. 123,804.

This invention relates to a composition for removing scales from steam boilers and it is an object of the invention to provide a composition of this kind which is adapted to be mixed with the water within the boiler and which functions while the boiler is in operation.

My improved composition consists of an admixture lime 1 qt., bluestone (well pulverized) $\frac{1}{2}$ lb., cornstarch $\frac{1}{2}$ lb., graphite $\frac{1}{2}$ lb.

A composition mixed in accordance with the foregoing formula is adapted to be used in connection with a sixteen ton locomotive boiler. For a sixty ton locomotive boiler the foregoing ingredients are used in twice the quantities stated.

It has been found in practice that generally two applications of the composition re-

sult in effective removal of scales within a 20 period of a week.

In practice, the composition is applied directly to the water within the boiler and functions while the boiler is in operation.

The lime serves to raise the scales while the bluestone hardens the scales and thereby cause it to smoothly loosen from the wall of the boiler. The graphite and corn starch serve to smooth up the inner boiler surface.

I claim:—

A composition for removing scales within a steam boiler consisting of lime, 1 qt., pulverized bluestone, $\frac{1}{2}$ lb., cornstarch, $\frac{1}{2}$ lb., and graphite, $\frac{1}{2}$ lb.

In testimony whereof I hereunto affix my signature.

WILLIAM F. STAFFORD.
